UNITED STATES PATENT OFFICE.

WILLIAM DOUGLAS ELLIOT, OF BIGTIMBER, MONTANA.

PAPER-BAG HOLDER.

1,273,341.

Specification of Letters Patent. Patented July 23, 1918.

Application filed May 13, 1918. Serial No. 234,202.

To all whom it may concern:

Be it known that I, WILLIAM DOUGLAS ELLIOT, a citizen of the United States, and a resident of Bigtimber, in the county of 5 Sweet Grass and State of Montana, have invented certain new and useful Improvements in Paper-Bag Holders, of which the following is a specification.

My invention is an improvement in paper 10 bag holders, and has for its object to provide a device of the character specified, wherein the bags may be supported in bundled relation, each size in a separate compartment, and wherein the packages are yieldingly 15 held, the packages being arranged in two series, one at each side of the holder, and the holding means for the packages of each series being provided with a common means for releasing the same to permit insertion of 20 the bags.

In the drawings:

Figure 1 is a side view of the improved holder;

Fig. 2 is a section on the line 2—2 of 25 Fig. 3;

Fig. 3 is a section on the line 3—3 of Fig. 2, looking in the direction of the arrows adjacent the line;

Fig. 4 is an enlarged detail section through 30 the supporting frame at the top thereof; and

Fig. 5 is a perspective view of one of the rod holders.

In the present embodiment of the invention, a suitable frame is provided, consisting 35 of a base 1 and standards 2, the said standards being four in number and being connected in pairs to the opposite sides of the base, the members of each pair converging toward the top and the pairs also converge 40 toward the top.

Here the standards are connected by top plates 3 and a series of transverse shelves or partitions 4 is arranged between the standards, the said partitions or shelves being secured 45 to the standards. A pair of rods 5 extends from the top to the bottom, at the center of the frame, the said rods passing through the partitions, and each partition is reinforced on its under face at the rods, as indicated at 6, and thus the rods divide 50 each shelf into two bag compartments for the packaged bags. The arrangement of the shelves provides for various size bags, the largest bags being at the bottom while the 55 smallest are at the top. The packages of

bags, indicated at 7, are laid upon the shelf, as shown in Fig. 2, with the bottoms of the bags outward, and the packages are yieldingly held to the shelf by means of rods 8. These rods are arranged transversely of the standards, and the ends of each rod pass through slots 9 in the standards, so that the rods can move vertically from one partition to the other.

In the present instance, each standard is 65 formed by two plates which are spaced apart at their adjacent edges to form the slots 9. Each of these rods 8 has an eye 10 at each end, and these eyes are engaged by hooks 11 on the arms of elbow levers 12, which are 70 pivoted to a vertically movable means, all of the elbow levers of each series being connected to a common moving means. Each of these elbow levers has an eye at the end remote from the hook, and it will be evident 75 that the hooks may be engaged with or disengaged from the eyes of any rod when desired.

The moving means for the rods is a pair of slides 13, each slide being mounted to 80 move on the outer face of a standard. The slides are slidably connected to the standards by means of screw bolts and nuts 14. These bolts pass through the slides 13 and through slots 15 in the standard, as shown in 85 Fig. 4. It will be noticed from an inspection of this figure that each slide is composed of two plates arranged parallel and spaced apart from each other, and the elbow levers 12 are pivoted between the plates upon 90 the rivets 16 which connect the plates. One of the bolts 14 is arranged at the top and the bottom of each slide, and the bolts 14 are passed through the slot from within outward, the heads of the bolts preventing outward movement of the slide away from the 95 standard.

Coil springs 17 and 18 are connected with the rods for pulling them downward on to the bags, and each of these springs is connected at its ends to a pair of rods, and to the rods which are on the same partition 4. The intermediate portion of each spring passes through an eye 19 on the adjacent end of the next lower shelf or partition 4, in 100 such manner that the springs are free to slide through the eyes 19. The spring 18 which engages the rods on the base 1 is connected at its ends to the rods, and the intermediate portion of the spring passes through 105 110

the eye 19^a connected with the lowermost partition 4. Near each rod the spring also passes through an eye 20 on the base. The slides 13 at each series of bag compartments 5 are connected to a roll 21 which is journaled in bearings 22 on the top of the frame. A flexible member 23 winds upon the roll at each slide, one end of the said member being connected to the roll, and the other end is 10 connected to a rod 24 which has an eye at one end for engagement by the flexible member, and an eye at the other end for engagement by the adjacent bolt 14. The slides are normally pulled downward by 15 springs 25, one being arranged at each end of the holder. This spring intermediate its ends passes through the eye 19^a before mentioned, and at its ends it engages eyes 26 on the two slides at that end.

20 A yoke shaped handle 27 is connected with each roll intermediate the ends of the roll for operating the same to lift the slides at that end of the holder. The arms of the yoke are connected with the roll. An extension member 28 in the form of a yoke is arranged at each end of each partition 4 and at each end of the base 1, these extensions serving to support the outer ends of the bags.

30 In use, the bags are laid upon the shelves, the roll being turned, as shown at the left of Fig. 1, to lift the slides. The rods being thus lifted, the bags may be inserted, and when the slides are released the bags will 35 be clamped down upon the shelves. After the bags have been inserted, the elbow levers are released from the rods as shown at the right of Fig. 1. When it is desired to remove a bag, it is pulled out from beneath the 40 holding rods.

I claim:

1. A paper bag holder comprising a stand having a plurality of series of shelves, the shelves of each series being arranged one 45 above the other for receiving bundles of bags of varying sizes, a rod slidably connected with the standard at each shelf and adapted to rest upon the bundle of bags to hold them on the shelf, springs normally 50 pressing each rod downwardly, a common lifting means for all of the rods of each series of bags and slidably connected with the stand and normally disconnected from the rod, and independent means at each shelf 55 for connecting the adjacent rod to the lifting means, the said means comprising elbow levers having hooks, the rods having eyes at their ends for engagement by the hooks, and the elbow levers having finger pieces for 60 permitting the same to be operated.

2. A paper bag holder comprising a stand having a plurality of series of shelves, the shelves of each series being arranged one 65 above the other for receiving bundles of bags of varying sizes, a rod slidably con-

nected with the standard at each shelf and adapted to rest upon the bundle of bags to hold them on the shelf, springs normally pressing each rod downwardly, a common lifting means for all of the rods of each series 70 of bags and slidably connected with the stand and normally disconnected from the rod, and independent means at each shelf for connecting the adjacent rod to the lifting means, each of the said lifting means comprising slides slidably connected with the standard at opposite sides thereof, a roller journaled at the top of the stand and having a handle, a flexible connection winding upon each roller at the adjacent slide and connected with the slide, and springs normally 75 pressing the slides downward.

3. A paper bag holder comprising a stand having a plurality of series of shelves, the shelves of each series being arranged one 80 above the other for receiving bundles of bags of varying sizes, a rod slidably connected with the standard at each shelf and adapted to rest upon the bundle of bags to hold them on the shelf, springs normally 85 pressing each rod downwardly, a common lifting means for all of the rods of each series of bags and slidably connected with the stand and normally disconnected from the rod, and independent means at each 90 shelf for connecting the adjacent rod to the lifting means.

4. A paper bag holder comprising a stand having a series of shelves arranged one 95 above the other upon which the bundles of bags are adapted to be placed, a rod arranged transversely of the stand above each shelf and slidably connected with the stand, a common moving means for all the rods and normally disconnected from the 100 rods and slidably connected with the stand, means at each rod for detachably connecting the moving means with the rod or for releasing the same from the rod, means at the top of the standard for lifting the moving means, said moving means comprising 105 slides at the opposite sides of the stand and slidably connected therewith, and elbow levers for each rod pivoted on the slides, and having hooks at one end, the rods having 110 eyes for engagement by the hooks.

5. A paper bag holder comprising a stand having a series of shelves arranged one 115 above the other upon which the bundles of bags are adapted to be placed, a rod arranged transversely of the stand above each shelf and slidably connected with the stand, a common moving means for all the rods and normally disconnected from the rods and slidably connected with the stand, means at each rod for detachably connecting the moving means with the rod or for releasing the same from the rod, means at the top 120 of the standard for lifting the moving means, said lifting means comprising a 125

roller journaled at the top of the standard and having a handle for oscillating the same, and flexible members winding at one end upon the roller and connected at the 5 other end to the moving means.

6. A paper bag holder comprising a stand having a series of shelves arranged one above the other upon which the bundles of bags are adapted to be placed, a rod arranged transversely of the stand above each shelf and slidably connected with the stand, a common moving means for all the rods and normally disconnected from the rods and slidably connected with the stand, 10 means at each rod for detachably connecting the moving means with the rod or for releasing the same from the rod, and means at 15

the top of the standard for lifting the moving means.

7. A paper bag holder comprising a stand having a series of supports for the bundles of bags, yielding means normally pressing each bundle of bags upon its support, a common means for lifting all of said yielding means to release the bags and normally disconnected from the bags, and independent means at each support for connecting the holding means of the adjacent pile of bags to the moving means. 20 25
